DISPENSING RACK

John M. Lieber, Detroit, and Roman Lieber,
Royal Oak, Mich.

Application August 18, 1949, Serial No. 4,581

Term of patent 14 years

(Cl. D80—10)

To all whom it may concern:

Be it known that we, John M. Lieber, a citizen of the United States, residing at Detroit, in the county of Wayne and State of Michigan, and Roman Lieber, a citizen of the United States, residing at Royal Oak, in the county of Oakland and State of Michigan, have invented a new, original, and ornamental Design for a Dispensing Rack, of which the following is a specification, reference being made to the accompanying drawing, forming part thereof.

Fig. 1 is a perspective view of a dispensing rack, showing my new design;

Fig. 2 is a side elevational view of the dispensing rack; and

Fig. 3 is a top elevational view of the dispensing rack.

We claim:

The ornamental design for a dispensing rack, as shown.

JOHN M. LIEBER.
ROMAN LIEBER.
